UNITED STATES PATENT OFFICE.

THOMAS ANDRESS, OF PITTSVILLE, WISCONSIN.

SAFETY-TIP FOR VEHICLE-TONGUES.

SPECIFICATION forming part of Letters Patent No. 406,188, dated July 2, 1889.

Application filed March 18, 1889. Serial No. 303,709. (No model.)

To all whom it may concern:

Be it known that I, THOMAS ANDRESS, a citizen of the United States, residing at Pittsville, in the county of Wood and State of Wisconsin, have invented certain new and useful Improvements in Safety-Tips for Vehicle-Tongues; and I do hereby declare the following to be a full, clear, and exact description of the invention, such as will enable others skilled in the art to which it appertains to make and use the same, reference being had to the accompanying drawings, and to the letters of reference marked thereon.

My invention has relation to certain new and useful improvements in safety-tips for vehicle-tongues; and it consists of the parts and details of construction, as hereinafter more fully pointed out and described in the accompanying drawings and specification.

The general object and purpose of my invention is to provide a pole-tip for vehicle-tongues, so constructed as to permit of the ready attachment or detachment of the neck-yoke, and which at the same time will provide against the detachment of the neck-yoke ring therefrom when the same is in position for use above the pole, and which shall be so constructed as to provide against the reins getting caught beneath the end thereof.

In the drawings forming a part of this application, Figure 1 is a view showing a vehicle-pole provided with my improved pole-tip; Fig. 2, a similar view of a vehicle pole or tongue embodying my invention, representing the neck-yoke ring as being secured in place. Fig. 3 is a detail view of my improved tip removed from the pole, and showing the tongue of the open loop raised to permit of the ready insertion of the neck-yoke ring therein. Fig. 4 is a cross-section on line $x-x$, Fig. 1; and Fig. 5, a longitudinal sectional view on line $y-y$, Fig. 1.

Similar letters of reference are used to designate corresponding parts throughout the entire specification and several views of the drawings.

The letter A is used to indicate the ordinary vehicle pole or tongue, and to which is secured my improved safety pole-tip. This tip is represented by the letter B; and it consists of a piece of metal so constructed as to form a rearwardly-extending portion C, which

rearward extension is made tubular and so shaped as to conform to the contour of the vehicle pole or tongue over which it fits, and 55 said tubular extension is provided with suitable holes or apertures b b, through which bolts c c pass in order to secure the same rigidly to said tongue or pole, so as to prevent the pulling off thereof. The outer end of the 6c tip is reduced or made flat, as shown at D, and has a portion thereof removed, so as to form an open loop E. The downwardly-extending portion e of the flat end of the pole-tip is provided in the front thereof with a recess or groove f, extending nearly to the bottom thereof, and into which is pivotally secured the tongue F. I also provide the upper wall f' of the loop with a recess or groove, into which fits the end of the tongue 70 F when the same is raised to permit of the insertion of the ring of the neck-yoke. The front hooked seat G of the pole-tip is also provided at its inner end with a groove or recess g, into which the end of the tongue F fits when brought into such a position as to close the opening h of the loop, as shown in Fig. 1, in order to provide against the outfalling of the neck-yoke ring by its own gravity.

The operation of my improved device is as follows: After securing the safety-tip over the vehicle-pole, and it is desired to secure thereto the neck-yoke, the tongue F, covering the opening of the loop, is pushed upward until its end rests in the groove formed in the 85 upper wall f' of the flat or reduced portion of the pole-tip, and while in this position the ring of the neck-yoke is passed into the loop E, wherein it is carried forward until it reaches the upper extremity of the forward 90 end of the loop. The tongue F is then allowed to fall into its normal position, so as to cover the opening h of the loop and thus prevent the withdrawal of the neck-yoke ring without re-raising the same, so as to uncover 95 the opening. It is obvious that when the neck-yoke is so secured the ring cannot become disengaged from the loop of its own accord, so that, should any accident occur—as, for instance, the breaking of a trace or whiffletree—the neck-yoke will still be maintained in a secure position and thus be prevented from falling off of the vehicle-tongue.

It will be further observed that inasmuch

as the ring of the neck-yoke, when the same is in use, as shown in Fig. 2 of the drawings, is carried to the extreme forward portion of the loop, the pole-tip, instead of projecting, 5 as is usually the case, in advance of the neck-yoke, is slightly behind the same, and thus the reins are prevented from catching under the end of the vehicle pole-tip in case the same should be allowed to hang loosely upon 10 the neck-yoke.

Having thus fully described my invention, what I claim as new, and desire to secure protection in by Letters Patent of the United States, is—

- 15 1. The combination, with a vehicle pole or tongue, the herein-described metallic safety-tip for attachment of the neck-yoke therein, consisting of the rearwardly-extending tubular portion adapted to fit over and be removably secured to the vehicle-tongue, and of the flat or reduced outer portion having an open loop formed therein to permit of the reception of the neck-yoke ring, of the tongue pivotally secured in the downwardly-extending 20 portion and adapted to close the opening of the loop for the retention of the neck-yoke ring therein, and the walls having grooves or recesses formed therein and into which
- 25

the end of the said tongue fits in its raised or lowered position, substantially as and for 30 the purpose herein set forth.

2. The herein-described safety-tip for neck-yokes, consisting of the rearwardly-extending tubular portion fitting over the vehicle-tongue and adapted to be secured thereto, 35 the flat or reduced outer portion, said outer portion having the inner depending slotted wall and the outer turned-under or hooked portion, forming a longitudinal curved slot between the upper edge of the hook and the 40 under edge of the body of the flat head of the tip, said under edge having a recess therein, the longitudinal slot also terminating at its forward end in an enlargement, in combination with the lever or tongue pivoted in the 45 depending slotted wall and adapted to close the opening between said depending wall and the inner end of hook and to have its free end rest in a recess formed in the upper edge of the end of said hook, as set forth. 50

In testimony whereof I affix my signature in the presence of two witnesses.

THOMAS ANDRESS.
